(57) **CLAIM**

The ornamental design for a monocle, as shown and described herein.

DESCRIPTION

FIG. 1 is a front perspective view of a monocle showing my new design;

FIG. 2 is a rear perspective view of the monocle;

FIG. 3 is a front view the monocle;

FIG. 4 is a rear view of the monocle;

FIG. 5 is a top view of the monocle;

FIG. 6 is a bottom view of the monocle;

FIG. 7 is a side view of the monocle;

FIG. 8 is a side view of the monocle;

FIG. 9 is a front perspective view of the monocle attached to a pair of glasses; and,

FIG. 10 is a rear perspective view of the monocle attached to a pair of glasses.

The broken lines in FIGS. 9 and 10 depicting a pair of glasses show environmental structure and form no part of the claimed design. All other broken lines in the drawings show portions of the monocle and form no part of the claimed design.
